UNITED STATES PATENT OFFICE.

EDWARD B. HESS, OF NEW YORK, AND JOSEPH M. STOUGHTON, OF YONKERS, NEW YORK,
ASSIGNORS TO ROYAL TYPEWRITER COMPANY, OF HOBOKEN, NEW JERSEY, A CORPO-
RATION OF NEW JERSEY.

WRITING-MACHINE.

No. 888,438.

Specification of Letters Patent.

Patented May 19, 1908.

Application filed March 29, 1905. Serial No. 252,722.

To all whom it may concern:

Be it known that we, EDWARD B. HESS, of the borough of Brooklyn, city and State of New York, and JOSEPH M. STOUGHTON, of the city of Yonkers, county of Westchester, and State of New York, citizens of the United States of America, have invented certain new and useful Improvements in Writing-Machines, of which the following is 10 a specification.

The object of this invention is to protect the working mechanism from dust and dirt either deposited from the atmosphere or resulting from the use of an eraser upon the 15 sheet in the machine: and a further object is to reduce the noises of impact and vibration.

The invention is particularly applicable to a front-stroke machine having a vertically disposed type bar segment and type 20 bars which lie with their heads toward the front of the machine.

The subject matter claimed is hereinafter specified.

In the accompanying drawing Figure 1 is 25 a top plan view: Fig. 2, a vertical longitudinal section: Fig. 3, a bottom plan view: Fig. 4, a sectional detail view of part of the bottom closure plate of the frame: Fig. 5, a perspective view of one of the two closure 30 plates disposed between the ribbon boxes and the carriage respectively on opposite sides of the printing point. Fig. 6, a bottom plan view of the ribbon box or cover: Fig. 7, a front elevation thereof: Fig. 8, a rear elevation: Fig. 9, a section on the line 9, 9: and Fig. 10, a detail view showing the platen and 35 light reflecting surface of the ribbon box which directs reflected rays of light upon the paper on the platen and particularly to the 40 printing point thereon.

The frame of the machine comprises a rectangular casting having vertically disposed front and end plates or walls and side plates or walls *a*. The open bottom of this casting 45 is completely closed by a bottom plate *b* secured thereto by a series of screws *c*. This plate may be formed of sheet metal, and may have struck-up depressions in its outer face as indicated at *d*. Such depressions may 50 receive rubber supporting buttons *e*, Fig. 4, which may be permanently secured in position by screws passing through the opening *d'* in the bottoms of the depressions. It is, however, preferred that rubber buttons or 55 cushions be omitted and that the entire bot-

tom face of the bottom closure plate be covered with a relatively thick sheet of comparatively soft rubber or felt *f*, Figs. 2 and 3. At the extreme front of the machine, the top is closed against admission of dust by a plate 60 *g* secured to the casting and by the stepped cover *h* for the banks of finger pieces *i* having stems *i'* that extend through the stepped cover plate and through a guide plate *i''* located beneath it. 65

A cover plate *j* through which the stems of the upper line or bank of keys pass, extends rearwardly, and its rear edge has the contour indicated by dotted line *j'* in Fig. 1,—the curve of the edge near each side of this plate 70 being made to conform to the ribbon bobbin not shown.

The ribbon box comprises two circular 75 housings *k*, *k*, that inclose the ribbon bobbins at each side, and are connected by an intermediate plate which is of the shape shown in Figs. 7, 8 and 9, having, preferably, an inclined or beveled top face *m* intermediate the ribbon boxes. This structure is provided with slots *m'* for traverse of the ribbon. 80 The front wall of the part *m* may be, and preferably is, straight and tangential to the circular housings of the ribbon bobbins, whereas the rear wall is of a height equal to the height of the housings and is located in 85 front of the rear walls thereof, as seen in Fig. 1. This ribbon box composed of the parts *k*, *m*, with the front and rear walls of the latter, covers the opening that would otherwise exist in rear of the upper bank of keys. The 90 rear wall of *m*, (Fig. 8), is cut away at the center, the upper edge of the opening so formed being lower at the center than at either end, the purpose being to afford a clearance at the center for the center type bar, and at the 95 ends, for the respective end type bars and beyond such necessary opening for clearance of the type bars, the front of the ribbon box is completely closed except for the slots *m'* in which the ribbon traverses. In rear of 100 each housing *k*, the top of the machine is closed by a plate shown in Fig. 5. The front edge of this plate has a segmental recess whose edge passes under the circular edge of the ribbon box. Its rear edge *o*, which is 105 straight, extends as far rearwardly as the notches or recesses *p* in the sides of the casting, which are to be occupied by the bottom rail of the carriage. The inner edge of the plate is curved as at *o'*, the curve conforming 110

to the path traversed by the head of the end type-bar and is also turned upwardly, the line of the bend or point at which the curve starts being indicated by o^2 , and the extreme 5 rear, inner, upwardly-curved edge is located immediately under the type-bar guide q , in rear of which is the ribbon vibrator q^1 , the line q^2 indicating the ribbon. Just at the rear of the type-bar guide, this plate is bent 10 downwardly, or formed with a vertical wall o^3 , and the angle between the upwardly extending curved part o^1 , and the vertical wall o^2 is flattened, as shown at o^4 , to afford a clearance for the ribbon. Extending between the sides of the castings and immediately 15 below the front edge o of these cover plates, is a vertical cross-plate r that forms the front wall of the opening at p , in which the base rail of the carriage lies, and serves to 20 deflect the dirt and grit of erasure from the type-bar bearings in the segment s . The ribbon vibrator q^1 extends upwardly between the back of the segment s , and the wall or partition r .

25 So far as mere dirt or grit of erasure is concerned, the dust guard composed of two plates or sections such as shown in Fig. 5 forms an effective protection to the type bar pivots. Since the rear edges of the dust 30 guard sections pass beyond the rear face of the type bar segment there is practically no possibility of the dirt of erasure falling into the bearings of the bars from the rear of the segment even were those bearings exposed 35 from the rear side as is the case in some forms of segments. Unless an erasure be made at the printing point, or, in other words immediately over the small opening between the contiguous edges of the two dust guard 40 plates through which opening the ribbon vibrator passes, there is practically no possibility of the dirt of erasure reaching the type bars or their pivots. Owing to the location 45 of the ribbon vibrator and type bar guide and because of their close proximity to the printing point it is not the custom of operators to make erasures directly at the printing point. The universal custom is to make 50 the erasure at either one side or the other. Any dirt of erasure would, therefore, fall 55 upon the dust guard plates and since their inner edges are curved upwardly, dirt of erasure falling thereon may be brushed away. For effective protection it is not necessary 60 that the space between the contiguous edges of these two dust sheds should be made so small as to merely permit the passage of the various type bars. They may, in fact, be as widely separated toward the front as the 65 designer of the machine desires without impairing their efficiency.

In rear of the depression p , p , there are at the sides of the machine and extending to the rear wall, cover plates t , t , between which 65 a space t' is left for the escapement lever and

other necessary upwardly extending parts. At each outer lower edge of each ribbon box housing is a downwardly extending lip or finger k' that has more or less resiliency and which pass through slots k^2 in the cover plates n , o , thereby serving not only to guide the ribbon box into proper position but to frictionally retain it.

As shown in Fig. 10 the rear wall m^2 of the part m on both sides of the central type bar opening therein, or the rear wall of the ribbon boxes, may be inclined, so that rays of light indicated by dotted lines x , will be reflected, as shown by dotted lines y , to the front face of the platen, increasing the illumination thereof. This inclined portion may extend between the dotted lines x y Fig. 8.

We claim as our invention:

1. In a front stroke writing machine, a dust and dirt excluding member located between the platen and ribbon boxes and comprising opposite parts separated by a space for passage of the type bars to the printing point, the inner edges of such parts being respectively curved, as at o^1 and turned upwardly to conform to the paths of the end type bars, and being each also formed with a vertical wall o^3 and having the edge or angle formed by the vertical wall flattened as at o^4 for passage of the ribbon.

2. In a front stroke writing machine, a dust and dirt excluding member located between the platen and ribbon boxes and comprising opposite parts separated by a space for passage of the type bars to the printing point, the inner edges of such parts being respectively curved, as at o^1 and turned upwardly to conform to the paths of the end type bars, and being each also formed with a vertical wall o^3 and having the edge or angle formed by the vertical wall flattened as at o^4 for passage of the ribbon, in combination with ribbon bobbin housings connected by an intervening part m serving to close the top of the frame between the housings and in front of the key board plates, said part m having its rear wall cut away for passage of the type bars to the printing point.

3. In a front stroke writing machine a ribbon bobbin box located in front of the platen and comprising housings for the bobbins rigidly and permanently connected by an intervening part constituting a partial cover to partly inclose the top of the machine.

4. In a front stroke writing machine a ribbon bobbin box comprising housings for the bobbins rigidly and permanently connected by an intervening part constituting a partial cover to partly inclose the top of the machine, and composed of a top, front and rear walls, the rear wall being cut away centrally for passage of the type bars to the printing point.

5. In a front stroke writing machine a

ribbon bobbin box comprising housings for the bobbins rigidly and permanently connected by an intervening part constituting a partial cover to partly inclose the top of the machine, and composed of a top, front and rear walls, the rear wall being cut away centrally for passage of the type bars to the printing point, and inclined rearwardly and downwardly adjacent the housings to form angularly disposed surfaces to reflect light rays to the printing point on the platen.

6. In a front stroke writing machine, a rectangular frame, a dust excluding and sound deadening closure comprising a plate entirely closing the bottom, and closure means for the top, composed of the key board plates, a ribbon bobbin box having housings connected by an intermediate part; and, interposed between the box and platen, plates separated longitudinally of the machine by a space for passage of the type bars to the printing point.

7. In a front strike writing machine, a platen, a vertically arranged type bar segment in which the type bars, that normally lie in substantial parallel lines with their heads toward the front, are pivoted, a dust shed composed of two sections arranged respectively with their inner ends closely adjacent the printing point and extending laterally therefrom with their front edges inclined outwardly whereby the type bar segment and type bar bearings therein are protected from dirt of erasure occurring at either side of the printing point.

8. In a front strike machine, type bars normally lying toward the front of the machine in substantially parallel lines, a segment in which they are pivoted and a dust shed arranged above the segment and composed of two sections whose inner ends are closely adjacent the printing point and which extend laterally and forwardly being more widely separated at their front ends.

45 9. In a front strike writing machine, a dust shed arranged above the chord of the arc in which the type bars are pivoted and extending from closely adjacent the printing point laterally towards the sides of the machine.

50 10. In a front strike machine, a platen, a centrally disposed ribbon vibrator and a centrally disposed type bar guide in front of the vibrator, a dust shed composed of two sections having their narrow inner ends contiguous the guide and extending laterally with their front edges inclined outwardly, combined with a vertically disposed type bar segment located below the dust shed and having bearings for the type bars.

11. A front strike writing machine comprising a platen, a centrally disposed ribbon vibrator and type bar guide, a dust shed composed of two sections whose narrow inner ends are contiguous to the guide and which

extend laterally with their front edges inclined outwardly, combined with a type bar segment located below said dust guard and provided with bearings for the type bars.

12. In a front strike writing machine, a platen, a vertically disposed support located below the platen provided with bearings arranged in an arc for the type bar, type bars pivoted in said bearings and normally lying substantially parallel with their heads toward the front, and a dust shed arranged above the segment and extending on either side of the printing point.

13. In a front strike writing machine, a platen, a transversely arranged segment below the platen and substantially in line below the printing line thereon, type bars pivoted therein in an arc and a dust shed located above a chord passing through the pivots of the end type bars and composed of two sections whose inner ends are arranged closely adjacent the printing point and which extend laterally and forwardly with their front edges inclined outwardly.

14. In a front strike machine, type bars normally lying toward the front of the machine in substantially parallel lines, a segment in which they are pivoted and a dust shed arranged above the segment and composed of two sections whose inner ends are closely adjacent the printing point, whose rear edge extends over the segment and which extend laterally and forwardly being more widely separated at their front ends.

15. In a front strike writing machine, a vertically disposed segment arranged below the platen, type bars pivoted therein and normally lying toward the front of the machine, and a dust shed extending at the rear over the segment, and from adjacent the printing point laterally and forward with a space between its front portions for passage of the type-bars to the printing point.

16. In a front strike writing machine, a vertically disposed segment arranged below the platen, type bars pivoted therein and normally lying toward the front of the machine, a ribbon guide located opposite the printing point on the platen, and a dust shed composed of two sections arranged respectively on opposite sides of the ribbon guide above the segment and having their inner edges toward the rear closely adjacent the ribbon guide and extending laterally and forwardly.

17. In a front strike writing machine, a vertically disposed segment arranged below the platen, type bars pivoted therein and normally lying toward the front of the machine, a ribbon guide located opposite the printing point on the platen, and a dust shed composed of two sections arranged respectively on opposite sides of the ribbon guide above the segment and having their inner portions turned or inclined upwardly with

their inner edges toward the rear closely adjacent the ribbon guide and extending laterally and forwardly.

18. In a front strike writing machine, a vertically disposed segment arranged below the platen, type bars pivoted therein and normally lying toward the front of the machine, a ribbon guide located opposite the printing point on the platen, and a dust shed composed of two sections arranged respectively on opposite sides of the ribbon guide above the segment and having their inner portions turned or inclined upwardly with their inner edges toward the rear closely ad-

15 jacent the ribbon guide and extending laterally and forwardly and extending at the rear over the segment.

In testimony whereof, we have hereunto subscribed our names.
